US00D957395S

(12) **United States Design Patent** (10) Patent No.: **US D957,395 S**
(45) Date of Patent: **** Jul. 12, 2022**

(54) **SCANNER**

(71) Applicant: **BROTHER INDUSTRIES, LTD.**,
Nagoya (JP)

(72) Inventor: **Nozomi Tanaka**, Nagoya (JP)

(73) Assignee: **BROTHER INDUSTRIES, LTD.**,
Nagoya (JP)

(**) Term: **15 Years**

(21) Appl. No.: **29/765,309**

(22) Filed: **Jan. 7, 2021**

(30) **Foreign Application Priority Data**

Jul. 7, 2020 (JP) ..... 2020-013814 D

(51) LOC (13) Cl. **14-02**

(52) U.S. Cl.

USPC **D14/422**

CLAIM

The ornamental design for a scanner, as shown and described.

DESCRIPTION

FIG. 1 is a perspective view of a scanner;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof;
FIG. 7 is a bottom plan view thereof; and,
FIG. 8 is a reduced perspective view thereof in an alternate position.

The evenly spaced broken lines depict unclaimed parts of the scanner and form no part of the claimed design.

1 Claim, 8 Drawing Sheets
